UNITED STATES PATENT OFFICE.

STEPHEN A. DOBYNE, OF ST. LOUIS, MISSOURI, ASSIGNOR TO CHAMPION SHOE MACHINERY COMPANY, OF ST. LOUIS, MISSOURI, A CORPORATION OF MISSOURI.

STRING NAILING-MACHINE.

1,091,299.

Specification of Letters Patent. Patented Mar. 24, 1914.

Application filed March 18, 1912. Serial No. 684,653.

To all whom it may concern:

Be it known that I, STEPHEN A. DOBYNE, a citizen of the United States, and residing at St. Louis, in the State of Missouri, have 5 invented certain new and useful Improvements in String Nailing-Machines, of which the following is a specification.

This invention relates to nailing machines, and more particularly to nailing machines 10 of the type known as string nailing machines.

This invention as to certain of its features is an improvement on the machine shown and described in Patent No. 1,026,028, granted May 14, 1912.

One of the objects of this invention is to arrange the mechanism and provide means whereby a fastener may be properly positioned in the fastener guiding and receiving throat so that it may be properly driven by the driver.

Further objects will appear from the detail description taken in connection with the accompanying drawings in which:

25 Figure 1 is a front elevation of a machine embodying this invention, and Fig. 2 is a similar view with the mechanism in another position.

Referring to the accompanying drawings, 30 15 designates the machine head which supports the fastener inserting mechanism. A driver 16 is mounted in the lower end of a driver bar 17 which is supported in bearings on the head and connected by a pitman 18 to a crank 19 on the drive shaft 20. A throat 21 is pivoted at 22 on the head and has coöperating therewith, a string nail guide 23 also pivoted at 22 and moved clockwise by means of a spring 24. A cutter 35 blade 25 is mounted upon an arm 25^a pivoted on a lever 26 and yieldingly connected therewith through a spring 26^a. The lever 26 is pivoted on the head and is provided with a fork embracing and engaging an eccentric 27 mounted upon the drive shaft. An awl 28 is mounted upon an awl carrier 29 which in turn is mounted for swinging and sliding movement in the machine head. The awl carrier is swung by means of a 40 45 lever 30 having a cam roll engaging a cam track in the cam wheel 31 and is slid by means of a lever 32 having a cam roll 33

engaging a cam 34. The throat is moved in a counter-clockwise direction by means of a lever 35 having a cam roll engaging a 55 cam surface on cam wheel 31.

The mechanism is substantially of the same construction as the mechanism shown and described in application Serial No. 724,680, filed October 8, 1912. During the 60 operation of the machine the awl carrier operates the awl to pierce and feed the work, and also engages and moves the throat from the position shown in Fig. 1 to the position shown in Fig. 2, and the 65 throat is returned by means of a spring and the arm 35, as fully described in said application.

During the operation of the machine the throat is moved into and out of alinement 70 with the driver and with the string nail guide. The cutter also operates to move the string nail guide to place the groove therein in alinement with the throat, and in the actual operation both the throat and the 75 string nail guide move simultaneously toward and from each other. As the cutter 25 is moved downwardly the spring 26^a is compressed and the cutter bears against the string nail guide so as to move the lower 80 end of the same to the right Fig. 1. As this cutter engages the top face of the throat further movement imparted through the lever 26 will cause the cutter to move to the right Fig. 1 and cut the lowermost nail from 85 the string. In Fig. 2 the parts are shown in position just after a nail has been severed. The cutter is now under tension and bears not only with considerable force against the string nail guide, but also upon the upper 90 face of the throat. If now the throat is moved back to position in alinement with the driver immediately after the nail has been severed, the cutter bearing on the head of the cut nail will tend to move the head 95 thereof to the left (Fig. 2) and thus displace it in the throat so that it will not be properly positioned with respect to the driver, thereby causing the driver to break. It is necessary that the driver passage be 100 wider at the top than the head of the nail so as to permit the lowermost nail to start to feed into the throat as the throat and string nail guide move into coöperative re-

lation. This construction although necessary, will cause the nail to be displaced in the throat by the cutter.

In accordance with this invention the eccentric 27 and the cam 34 are so constructed and so positioned relatively on the drive shaft and with respect to their fork and cam roll, that the pressure of the cutter on the upper face of the throat will be relieved before the throat starts to swing back into alinement with the driver. This is shown in Fig. 2. In this figure the eccentric 27 is at dead center with respect to its fork and is ready to start to move the lever 26 clockwise. The cam 34 is however at this time in full engagement with its cam roll 33 and will remain in engagement therewith while the drive shaft turns through a short arc. The lever 26 will therefore be swung on its pivot for a short distance in a clockwise direction before the awl begins to move to the right and before the throat begins to move back to its position in alinement with the driver. The tension of the spring 26^a (which is compressed when the parts are in the position shown in Fig. 2) is thus relieved so as to relieve the pressure of the cutter on the throat and on the head of the nail in the driver passage before this throat starts to move back into alinement with the driver. The parts are so arranged as not only to relieve the tension of the spring, but also to raise and retract the cutter a short distance from the upper face of the throat before the throat starts to move back. As the pressure of the cutter is thus relieved, this cutter will not bear upon the head of the nail in the throat, so that this nail is not displaced when the throat is moved back into alinement with the driver.

The throat is shown and described in my divisional application Serial No. 774,379, filed June 18, 1913.

It is obvious that various changes may be made in the details of construction without departing from this invention, and it is therefore to be understood that this invention is not to be limited to the specific construction shown and described.

Having thus described the invention what is claimed is:

1. In a fastener inserting machine, the combination with a driver, a movable die member, and a coöperating cutter, of means for moving said die member and cutter into and out of coöperative relation constructed and arranged to relieve the pressure of said cutter on the cut nail before said die member and cutter begin to move out of coöperative relation.

2. In a fastener inserting machine, the combination with a driver, a fastener stock guide, a die member, and a coöperating cutter, of means for moving said guide and die member into and out of coöperative rela-

tion, means for operating said cutter to cut a fastener from the fastener stock constructed to relieve the pressure of said cutter on the cut nail before said first means operates to move said guide and die member out of coöperative relation.

3. In a fastener inserting machine, the combination with a driver, a fastener stock guide, a throat, and a cutter coöperating with said throat, of operating means for moving said throat into and out of alinement with said driver, and means for operating said cutter to cut a fastener from the fastener stock, the operating means for said throat and cutter being constructed and arranged to relieve the pressure of said cutter on the cut fastener before said throat begins to move into alinement with said driver.

4. In a fastener inserting machine, the combination with a driver, a fastener stock guide, a throat forming a die, and a coöperating cutter, of operating means for moving said throat into and out of alinement with said driver, and means for operating said cutter to cut a fastener from the fastener stock, the operating means for said throat and cutter being constructed and arranged to relieve the pressure of said cutter on the head of the cut fastener in said throat before said throat begins to move into alinement with said driver.

5. In a fastener inserting machine, the combination with a driver, a fastener stock guide, a throat, and a cutter coöperating with said throat, of operating means for moving said throat into and out of alinement with said driver, and means for operating said cutter to cut a fastener from the fastener stock, the operating means for said throat and cutter being constructed and arranged to begin the retracting movement of said cutter before beginning to return said throat into alinement with said driver.

6. In a fastener inserting machine, the combination with a driver, a fastener stock guide, a throat, and a cutter coöperating with said throat, of operating means for moving said throat into and out of alinement with said driver, and means for operating said cutter to cut a fastener from the fastener stock while said throat is out of alinement with said driver, the operating means for said throat and said cutter being constructed to partially retract said cutter before the throat begins to move into alinement with said driver.

7. In a fastener inserting machine, the combination with a guide for a string of connected nails, a driver, a throat movable into and out of alinement with said driver, and a feeding and cutting member constructed to feed and cut the string and position a cut fastener in said throat, and operating means constructed to relieve the

pressure of said feeding and cutting member on the fastener in said throat before said throat moves into alinement with said driver.

5 8. In a fastener inserting machine, the combination with a guide for a string of connected nails, a driver, a throat movable into and out of alinement with said driver, and a feeding and cutting member constructed to feed the string into said throat and co-operate therewith to cut a fastener from the string, and operating means constructed to partially retract said feeding and cutting member before said throat begins to move into alinement with said driver.

10 9. In a fastener inserting machine, the combination with a guide for a string of connected nails, a driver, a throat movable into and out of alinement with said driver, and

a feeding and cutting member constructed to feed the string into said throat and co-operate therewith to cut a fastener from the string, and operating means constructed to relieve the pressure of said feeding and cutting member on said throat before imparting movement to said throat to return it into alinement with said driver. 25

10 10. In a machine of the class described, a throat, and a removable resilient cutting die mounted on said throat, said die being bowed upwardly at its center with respect to said throat. 30

In testimony whereof I affix my signature in presence of two witnesses.

STEPHEN A. DOBYNE.
